CHARCOAL OVEN

Anthon H. Turner, Kingfisher, Okla., assignor to
Turner and Sons, Kingfisher, Okla.

Filed June 23, 1970, Ser. No. 23,622

Term of patent 14 years

Int. Cl. D7—02

U.S. Cl. D81—10

FIG. 1 is a side elevational view of a charcoal oven constructed in accordance with the present invention,

FIG. 2 is an elevational view of the other side of the charcoal oven shown in FIG. 1,

FIG. 3 is a top plan view of the charcoal oven of FIG. 1,

FIG. 4 is a bottom view of the charcoal oven of FIG. 1,

FIG. 5 is an elevational view of one end of the charcoal oven of FIG. 1, and

FIG. 6 is an elevational view of the other end of the charcoal oven of FIG. 1, the chimney being shown fragmentarily for convenience of illustration.

I claim:

The ornamental design for a charcoal oven, substantially as shown and described.
